UNITED STATES PATENT OFFICE.

WILLIAM S. BOWMAN, OF ORANGEVILLE, PENNSYLVANIA.

GAME APPARATUS.

Application filed March 23, 1922. Serial No. 546,057.

To all whom it may concern:

Be it known that I, WILLIAM S. BOWMAN, a citizen of the United States, residing at Orangeville, in the county of Columbia and ⁵ State of Pennsylvania, have invented certain new and useful Improvements in Game Apparatus, of which the following is a specification.

This invention relates generally to games ¹⁰ and toys, and more particularly to a game in which the success of the player is directly dependent upon his or her dexterity and skill in the manipulation of the apparatus.

More specifically the invention embodies ¹⁵ a game board upon the surface of which are a plurality of spherical bodies, hereinafter called balls. The surface of the board is provided with a plurality of compartments, pockets, or pens, and it is the object of the ²⁰ player to so tilt and otherwise manipulate the board, that the balls will gravitate into said pens.

A further object of the invention is the identification of certain pens with certain ²⁵ of said balls, the game being successfully terminated when all the pens contain only balls of the same identification as that pen, and no balls are unpenned.

Other objects of the invention are the ³⁰ provision of obstacles preventing the direct entrance of balls into the pens; the prevention of the easy removal of a ball from the wrong pen; the provision of undulating upright surfaces against which the periphery ³⁵ of the balls contact, whereby the speed of the balls is retarded and further movement is impeded; the provision of means whereby, with difficulty, a ball may be jumped out of the wrong pen into the correct one, said ⁴⁰ means also operating, upon tilting the board 180 degrees, to release all the balls from the pens for a repetition of the game.

Other objects of the invention will be made apparent in the following specifications and the drawings forming a part ⁴⁵ thereof.

In said drawings:

Figure 1 is a plan view of my improved game board.

Fig. 2 is an enlarged perspective view of the pens.

Fig. 3 is a section, on line 3—3 of Fig. 1.

Fig. 4 is a detail view showing a ball lodged in a depression in one of the vertical surfaces, and

Fig. 5, is a detailed view of one of the doors guarding the pens.

Now referring specifically to the drawings, the board A is provided with a floor X, and enclosing side walls C, a transparent ⁶⁰ cover D being preferably provided, as shown in Fig. 3.

Centrally located upon the surface X is a circular fence 1, provided with fences 2, 2, at right angles to each other, and dividing ⁶⁵ that part of the surface X, enclosed by the fence 1, into four pens B, W, Y, R, of equal area.

The fence 1 is apertured at the front of each of the pens, and a gate 3, adapted to ⁷⁰ cover each aperture, is pivotally mounted upon the fence. As shown in Figs. 2 and 5, each gate 3 is provided with ears which are turned over a rail of the fence 1, permitting swinging movement of the gate. ⁷⁵ Since each gate is wider than the associated aperture, and since they are mounted upon the inside of the pens, it is obvious that the gates may swing inwardly towards the pen, ⁸⁰ but not outwardly.

Each of the fences 2, forming the walls of the pens, is cut away at its top, to form the openings 4, the openings between the pens Y and B, B and W, and W and R, being centrally disposed with respect to the fence ⁸⁵ which divides these pens. The fence between the pens Y and R is cut away so as to form the opening 4 at the end thereof which connects with the fence 1, the latter being provided with a similar opening 5, ⁹⁰ as clearly shown in Fig. 2.

Upon the surface X, and directly opposite each gate 3, is a fence 6, preferably of segmental shape, and concentric with the fence 1.

The floors of the pens are differently colored, that of the pen B being blue, the pen W, white, the pen R, red, and the pen Y, ⁹⁵ yellow.

The spherical members, or balls 7, hereinbefore referred to, are of a size to permit their passage through the apertures guarded by the gates 3, and through the aperture 4 above referred to. Any convenient number of balls may be used in playing the game, but each of the balls 7 must be colored similarly to the floor of one of the pens B, W, R, Y, or the floors and the balls may, in some other manner, be identified as belonging to the same classification. I prefer to use ¹⁰⁰ 105 110

twelve balls 7, as illustrated in the drawings, three of which are white, three red, three blue, and three yellow, but it is obvious that the number of the balls may be varied, as may also be their color, so long as the balls are respectively colored the same as the floor of the pen in which they are ultimately to be located.

I also utilize another ball 8, which ball 10 may be of a neutral color, and must be larger than the balls 7, so as not to be able to pass through the apertures guarded by the gates 3.

In playing the game, all of the balls 7, 15 here shown as twelve, are upon the floor X, outside of the pens. In the terminology of the game, the balls are called "pigs", and it is the object of the game to so manipulate the board that all of the "pigs" of one color 20 may ultimately be located in the pen of that color, and no "pig" be left out of a pen. The larger ball 8 is called the "dog", and rolls against the "pigs" 7 and chases them into their respective pens, but cannot itself 25 enter a pen, because of its size. With the "pigs" in their respective pens, and the "dog" at rest, the game is finished.

In order to release the "pigs" from the pens, to start the game anew, the board is 30 held upside down. As shown in Fig. 3, there is some clearance between the bottom of the glass cover D and the top of the fences 2. When the board is inverted the balls 7 fall upon the cover D, and, by shaking the board the balls finally pass through the apertures 4 and out of the aperture 5, to the open field. Or, when the board is inverted, the pivoted gates 3 fall backwardly until their lower edges rest upon the surface of the cover D. In this inverted position, if the board is sharply jerked up and down, the "pigs" will pass outwardly 35 through the apertures in the fence 1, normally guarded by the gate 3, the gate now being swung inwardly to uncover said aperture.

The apertures 4, in the fences 2, serve 40 also to permit a "pig" 7 to jump from the wrong pen into his proper pen. Let us assume that a white "pig" enters the red pen. In the absence of any means for getting him out, the game is lost as soon as a "pig" enters a pen of the wrong color, since, in the absence of any provision to the contrary, the "pig" cannot get out of that pen, and the game cannot be successfully terminated. If the board is dexterously manipulated 45 however, to bring the foreign "pig" to a position such as shown in dotted lines, Fig. 2, immediately adjacent the opening 4, in the fence 2, and the board tilted from the front edge upwardly and then bodily moved downwardly and sharply jerked upwardly, the foreign "pig" may be caused to jump over and through the opening 4 and into

his home pen. Obviously it is sometimes necessary for the "pig" to make two jumps before getting home, or he may be jumped out via openings 4-5, and thence led in through the gate of his home hole.

I prefer to make all of the fences 1, 2 and 6, of wire fabric, as shown in the drawings, and for two reasons, first, because this material lends realism to the appearance of the fences, and, secondly, because it presents a hill and valley construction against which the balls cannot run freely. Whenever a ball is temporarily detained in one of the valleys of the wire mesh, the "dog" 8 is caused to roll against and dislodge it. Manifestly the game may be played if the fences are constructed of other material however, and if the surfaces of the material are smooth and unbroken.

It is obvious that various modifications are possible, in the number of pens, and the number of balls, and the colors used. Also, with the apparatus as broadly described, the game may be played in various ways and under various rules. The cover plate D may be dispensed with, if found desirable. My invention however, is broad enough to include all such embodiments and modifications as fall fairly within the scope of the appended claims.

I claim:

1. A game apparatus comprising a surface provided with an enclosure marked to indicate a certain classification, a similarly marked member adapted for gravitation over said surface and to enter said enclosure, means adapted to permit entry of said member into said enclosure and to prevent egress therefrom, and a separate exit from said enclosure remote from said surface, substantially as described.

2. A game apparatus comprising a surface provided with an enclosure, partitions dividing the enclosure into a plurality of compartments each marked to indicate a separate classification, a plurality of members adapted to gravitate over said surface and to enter said enclosure, each member being marked to indicate the classification of one of said compartments, means adapted to permit entry of said members into each compartment but preventing egress therefrom, and apertures in said partitions permitting egress from each compartment.

3. A game apparatus comprising a surface provided with a plurality of compartments having partitions therebetween, each compartment being marked to indicate a separate classification, a plurality of members adapted to gravitate over said surface and each marked to indicate the classification of one of said compartments, means adapted to permit entry of said members into said compartments but to prevent egress therefrom, and apertures in said partitions

affording communication between all said compartments.

4. A game apparatus comprising a surface provided with an enclosure, partitions dividing said enclosure into a plurality of compartments, members adapted to gravitate over said surface and to enter said compartments, means permitting entry of said members into said compartments but preventing egress therefrom, and apertures in said partitions whereby any and all members may be led outside of said enclosure. 10

5. A game apparatus comprising a surface provided with walls forming an enclosure, a member adapted for gravitation over said surface, an aperture in one of said walls adapted to permit entry of said member into said enclosure, an element pivoted to said wall and adapted to permit access of 15 said member to said enclosure but to prevent egress of said member, and an aperture in another wall of said enclosure adapted to permit egress of said member, substantially as described. 20

25 6. A game apparatus having a surface provided with a wall forming an enclosure, partitions dividing said enclosure into compartments, apertures in the wall of said enclosure, members adapted to gravitate over the said surface and to enter said apertures, elements carried by said wall and normally covering said apertures and adapted to permit entry of said members into said compartments but to prevent egress there- 30

35 from, and apertures in said partitions and said wall, whereby said members may be led out of all of said compartments and said enclosure, substantially as described.

40 7. A game apparatus comprising, in combination with members adapted to gravitate over a surface, a wall forming an enclosure on said surface, said enclosure being provided with partitions dividing it into a plurality of compartments, each compartment 45 being provided with an entrance aperture for said members, extending through said wall, and with an exit aperture for said members extending through one of said partitions, substantially as described.

50 8. A game apparatus comprising, in combination with members adapted to gravitate over a surface, a wall forming an enclosure on said surface, said enclosure being provided with partitions dividing it into a plurality of compartments, each compartment 55 being provided with an entrance aperture for said members, extending through said wall, and with an exit aperture for said members extending through one of said partitions, 60 and means permitting entry of said members through said entry aperture, but preventing egress therethrough, substantially as described.

65 9. A game apparatus, including a surface and members adapted for gravitation there-

over, comprising an enclosure having a wall and apertures in said wall permitting ingress of said members into said enclosure, means preventing egress of said members through said apertures, and barriers on said surface, spaced from said wall, and presenting a surface composed of hills and valleys, substantially as described. 70

10. A game apparatus, including a surface and members adapted for gravitation there- 75 over, comprising a wall forming an enclosure on said surface, partitions dividing said enclosure into a plurality of compartments, apertures in said walls, members adapted to gravitate over said surface and to pass through said apertures, barriers on said surface located opposite said apertures and spaced from said wall, said wall, said partitions and said barriers presenting surfaces of hill and valley construction, substantially 80 as described. 85

11. A game apparatus, including a surface and members adapted for gravitation there- over, comprising a wall forming an enclosure on said surface, partitions dividing said enclosure into a plurality of compartments, apertures in said walls, members adapted to gravitate over said surface and to pass through said apertures, barriers on said surface located opposite said apertures and 90 spaced from said wall, said wall, said partitions and said barriers presenting, on both sides, surfaces of hill and valley construction, substantially as described. 95

12. A game apparatus comprising a surface provided with a wall forming an enclosure on said surface, partitions dividing said enclosure into a plurality of compartments each marked to indicate a classification different from that of any other compartment, apertures in said wall affording admission to said compartments, a plurality of balls adapted to gravitate over said surface and pass through said apertures, each ball being marked to denote a classification 100 the same as that of one of said compartments, a gate for each aperture, pivotally mounted to swing inwardly, under contact by said balls, means preventing said gates 105

110 from swinging outwardly, another ball adapted to gravitate over said surface and of a size preventing its passage through said apertures, ports in the upper edges of said partitions permitting the passage of a ball 115 from one compartment to another, a port in the upper edge of said wall, permitting the exit of balls from said enclosure, barriers on said surface located outside of said enclosure and opposite said apertures, said walls, said partitions and said barriers presenting, on both sides, vertically disposed surfaces of hill and valley construction, substantially as described. 120

125 13. A game apparatus comprising a surface provided with an enclosure, partitions 130

4

in said enclosure dividing the latter into compartments, a member adapted for gravitation over said surface and to enter said enclosure, means movable to permit entry of said member into said enclosure, but to prevent egress therefrom, an aperture in the top portion of said partitions permitting the passage of said member between the several compartments, when said member is out of contact with said surface, substantially as described.

14. A game apparatus comprising a surface provided with an enclosure, partitions in said enclosure dividing the latter into compartments, a member adapted for gravitation over said surface and to enter said enclosure, means movable to permit entry of said member into said enclosure, but to prevent egress therefrom, and an aperture at the top of said enclosure permitting egress of said member when the latter is out of contact with said surface, substantially as described.

15. A game apparatus comprising a surface provided with an enclosure, partitions in said enclosure dividing the latter into a plurality of compartments, a member adapted for gravitation over said surface and to enter said enclosure, means movable to permit entry of said member into said enclosure, but to prevent egress therefrom, an aperture in the top portion of each partition permitting said member to pass between the said compartments when said member is out of contact with said surface, and an aperture in said enclosure permitting the egress of

said member when the latter is out of contact with said surface, substantially as described.

16. A game apparatus comprising, in combination with a surface and a member adapted for gravitation thereover, a circular enclosure on said surface constructed to provide hills and valleys on both sides thereof, a plurality of partitions in said enclosure dividing the latter into compartments, said partitions presenting hill and valley surfaces on both sides, means permitting ingress of said member to said enclosure but preventing egress therefrom, and means whereby said member may pass from one compartment to another, substantially as described.

17. A game apparatus comprising, in combination with a surface and a member adapted for gravitation thereover, a circular enclosure on said surface constructed to provide hills and valleys on both sides thereof, a plurality of partitions in said enclosure dividing the latter into compartments, said partitions presenting hill and valley surfaces on both sides, means permitting ingress of said member to said enclosure but preventing egress therefrom, means whereby said member may pass from one compartment to another and means permitting egress of said member from said enclosure, substantially as described.

In testimony whereof I affix my signature.

WILLIAM S. BOWMAN.
